(57) **CLAIM**

The ornamental design for a golf tool, as shown and described.

DESCRIPTION

FIG. 1 is a perspective view showing the new, original, and ornamental design of a golf tool;

FIG. 2. is a top plan view thereof;

FIG. 3 is a bottom plan view thereof;

FIG. 4 is a right elevation view thereof, the left being a mirror image;

FIG. 5 is a rear elevation view thereof; and,

FIG. 6 is a front elevation view thereof.

The broken lines shown in the drawings represent environmental subject matter and form no part of the claimed design.
